(57) CLAIM

The ornamental design for pants, as shown and described.

DESCRIPTION

FIG. 1 is a rear perspective view of pants showing a first embodiment of my new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a rear perspective view of pants showing a second embodiment of my new design;

FIG. 7 is a front elevation view thereof;

FIG. 8 is a rear elevation view thereof;

FIG. 9 is a left elevation view thereof; and,

FIG. 10 is a right elevation view thereof.

The thinner, shorter broken lines (as opposed to the thicker, longer broken lines) shown in FIGS. 1-10 designate stitching, which is part of the claimed design. The thicker, longer broken lines (as opposed to the thinner, shorter broken lines) shown in FIGS. 1-10, illustrate environment and form no part of the claimed design.
